(57) **CLAIM**

The ornamental design for a radiation shielding container lid, as shown and described.

DESCRIPTION

FIG. 1 is a perspective view of a radiation shielding container lid;

FIG. 2 is a top plan view thereof;

FIG. 3 is a cross sectional view thereof taken along line 3—3 in FIG. 2;

FIG. 4 is a cross sectional view thereof taken along line 4—4 in FIG. 2;

FIG. 5 is a front elevational view thereof, the rear elevational view being identical thereto;

FIG. 6 is a left side elevational view thereof, the right side elevational view being identical thereto; and,

FIG. 7 is a bottom plan view thereof.

The broken lines in the figures are included for the purpose of illustrating portions of the radiation shielding container lid that form no part of the claimed design.
